Patented Feb. 18, 1969

213,340

ENVELOPE FEEDER FOR A PRINTING PRESS

Robert B. Burns, 1601 Travis, Fort Worth, Tex. 76104

Filed June 20, 1967, Ser. No. 7,527

Term of patent 14 years

U.S. Cl. D64—11

Int. Cl. D18—99

Fig. 1

Fig. 3

Fig. 2

Fig. 4

FIG. 1 is a front perspective view of an envelope feeder for a printing press embodying my new design;

FIG. 2 is a top plan view thereof;

FIG. 3 is a side elevational view; and

FIG. 4 is a front elevational view thereof.

I claim:

The ornamental design for envelope feeder for a printing press, as shown.
